P. DAVEY

SPARK GAP APPARATUS

Filed August 28, 1922

Patented Aug. 3, 1926.

1,594,457

UNITED STATES PATENT OFFICE.

PETER DAVEY, OF LONDON, ENGLAND, ASSIGNOR TO HERBERT KENNEDY & COMPANY
LIMITED, OF LONDON, ENGLAND.

SPARK-GAP APPARATUS.

Application filed August 28, 1922, Serial No. 584,732, and in Great Britain March 29, 1921.

This invention relates to spark gap apparatus.

It will be understood that in stroboscopic apparatus giving frequent light flashes by means of a series of oscillatory discharges produced by current interrupting mechanism driven by a running machine it is most desirable to have one definite flash accurately timed to occur at a predetermined position or successive positions of the machine in its cycle. It is therefore an object of this invention to stop the return and and subsequent pulsations and accordingly I provide a spark-gap in combination with such apparatus, so arranged or adjusted as to permit the passage of the first discharge, but too wide to be bridged by the return and subsequent pulsations from any single discharge.

A further object of the invention is to provide an improved form of portable spark-gap apparatus which may be combined with a holder for a lamp of the electron discharge type.

A further object is to provide in an apparatus flashes of light, means whereby a gap in the circuit (either in series or in parallel) of the discharge apparatus may be adjusted to suit variations of speed or other conditions.

One form of the invention is illustrated in the accompanying drawings in which:—

Fig. 1 is a section,

Fig. 2 is a side elevation at a right angle to Fig. 1 with lamp and reflector removed.

Fig. 3 is a plan view of the lamp-holder.

The lamp 1 of the electron discharge type contacts with a master lamp holder of which the plunger 2 is earthed, and the plunger 3 is connected to one terminal 4 of the spark gap device. This terminal 4 is in a fixed position within a wire gauze envelope 5 to enable the device to be used if necessary in an explosive atmosphere and a second terminal 6 with a screwed shank 6^a is adjustable by means of the milled nut 6^b to vary the gap between the terminals.

The lamp holder and spark gap apparatus are both carried by a handle 7 provided with a hook 8 by which it may be conveniently hung in a fixed position when required, and the electrical (oscillatory) supply is introduced, by means of flexible cable 9 carrying two conductors, one of which is

sweated into a sleeve 10 so making contact with the adjustable terminal of the gap and the other (or earthed conductor) is clamped under the head of a set screw 11, so making contact through the metallic parts of the holder and wire 12 with the plunger 2.

In order to put other electron discharge lamps in circuit with the same spark gap device a transverse plug opening is made having a spring 13 in contact with the fixed spark gap terminal and the groove 7^a and eye 7^b are formed in the handle to carry the supplementary lead or leads.

I claim:—

1. In stroboscopic apparatus the combination of an electron discharge lamp, means to supply oscillatory electrical discharges at very short but comparatively gradually variable intervals so as to produce flashes of light from said lamp, a spark-gap device in series with said lamp, and means to vary the spark-gap so as to render inoperative to produce said flashes all subsequent pulsations under all the various conditions of the said oscillatory supply.

2. A form of the apparatus set forth in claim 1 including also a portable holder carrying both said lamp and said means to vary the spark-gap, whereby an observer can simultaneously both direct the lamp upon any body or mechanism under study and adjust the spark-gap in accordance with the visual sensation received from the said body or mechanism.

3. Method of defining stroboscopic images produced in known manner by periodic light flashes from an electron discharge lamp played upon a body under observation, consisting in viewing the body by the light of said flashes and varying a spark-gap in series with said lamp until a single clear image is obtained.

4. Method of maintaining clear stroboscopic images of bodies moving periodically at varying speeds, said images being produced in known manner by means of light flashes at corresponding periods from an electron discharge lamp, consisting in placing a spark-gap in series with said lamp and varying said spark-gap in accordance with any indications of varying appearance of the body as the speed varies.

In testimony whereof I affix my signature.

PETER DAVEY.
